UNITED STATES PATENT OFFICE.

CURTIS H. HODGKINS, OF ATTLEBORO, MASSACHUSETTS.

JEWELRY-POLISHING DEVICE.

No. 881,583.

Specification of Letters Patent. Patented March 10, 1908.

Application filed March 25, 1907. Serial No. 364,344.

To all whom it may concern:

Be it known that I, CURTIS H. HODGKINS, a citizen of the United States, residing at Attleboro, in the county of Bristol and State of Massachusetts, have invented a new and useful Jewelry-Polishing Device, of which the following is a specification.

My present invention relates to polishing devices, and more especially to that class adapted for use in polishing and burnishing jewelry and similar small objects while they are immersed in a suitable cleansing solution, and it has for its object to provide a device of this character that is capable of polishing or burnishing a considerable quantity of jewelry in a relatively short time, the receptacle for the jewelry being immersed in a suitable cleansing solution and having its interior so formed that the articles being operated on are subjected to a tumbling and rolling action that will insure the exposure of every surface thereof to the polishing medium, so that uniformity in the polishing and burnishing is secured.

Furthermore, it has for its object to provide a device of this character that is so simple that it may be constructed cheaply and is not liable to need repairs, and the receptacle for the articles to be polished is readily accessible and removable to permit introduction and removal of the articles before and after the polishing and burnishing operation.

To these and other ends, the invention comprises the various novel features of construction and arrangement of parts hereinafter more fully described and pointed out particularly in the claims appended hereto.

In the accompanying drawings:—Figure 1 represents a central vertical section of a polishing or burnishing machine constructed in accordance with my present invention. Fig. 2 is a perspective view of the oscillatory receptacle for the articles to be polished or burnished. Fig. 3 is a detail view of an operating crank and its latch for detachably locking the receptacle thereto. Fig. 4 is a sectional view of the co-operating portions of the crank arm and the trunnion for the receptacle.

Corresponding parts in the several figures are indicated throughout by similar characters of reference.

The machine shown in the present embodiment of my invention is of that type wherein the articles while being polished or burnished are subjected to the cleansing and washing action of a suitable solution, and it comprises,

in the present instance, a tank 1 of any desired or suitable dimensions and provided with a lid 2 for controlling access thereto, the tank being supported on legs or other means of support 3.

The receptacle for the articles to be polished or burnished is mounted to operate within the tank, the receptacle embodying, in the present instance, a hollow box or casing 4 preferably of a polygonal form, the box shown in the present instance being in the form of a hexagon. One of the sides, as 5, is hinged at its edges, as at 6, in order to permit access to the box or receptacle in order to permit introduction or removal of the objects to be polished relatively thereto, some suitable means such as a catch 30 being preferably provided for securing the door thus provided in closed position during the polishing or burnishing operation. The sides of the box are provided with one or more openings 7 covered by a wire net or gauze 8 to permit entrance and exit of the washing or cleansing solution, the wire gauze or mesh serving to prevent loss of the jewelry or other articles. The inner surfaces of the sides of the box or receptacle are provided each with a plurality of inwardly extending ribs 9, the ribs on one side of the box having a pitch or inclination 85 toward one end of the box, while those on the next adjacent side have an inclination or pitch leading toward the opposite end of the box, the ends of the several ribs of each series abutting those of the next series to form substantially continuous zig-zag ribs extending around the inner side of the box or receptacle.

The rear head of the box is provided with an axially arranged trunnion 10 having a journal thereon adapted to co-operate with the conical recess 11 formed in a bearing block 12, the latter being secured to the rear of the tank. The other head of the box is provided with a trunnion 13 having a reduced end 14 that is angular in cross section, the end of this trunnion in the present instance being square and forming a shank adapted to fit into a correspondingly shaped recess 15 extending inwardly from the outer end of a crank arm 16, the latter being provided at its inner end with a collar portion 17 adapted to be secured to the inner end of an operating shaft 18 by means of a set screw or other suitable means 19. By reducing the end of the trunnion 13 to provide an operating shank, a shoulder 20 is formed that is arranged to

coöperate with a rear side of the crank arm 16, the coöperative relation of these parts serving to sustain the end thrust between the journal 10 and its bearing 12 and thereby preventing disengagement of these parts.

In order to obtain the operating crank in coöperative relation with its respective trunnion during the polishing or burnishing operation, a latch is provided that serves to lock these parts in coöperative relation when the receptacle is inserted into the tank, and also enables the receptacle to be readily removed from the tank when the polishing or burnishing operation is completed.

15 The latch shown in the present embodiment of the invention comprises a leaf spring 21 rigidly fixed at one end by the screws 22 to one side of the crank arm 16, the free end of the spring being provided with a pawl or 20 dog 23 which extends laterally over the outer end of the crank arm and the slot formed therein, and serves to coöperate with the angular shank when the latter is operatively connected to the crank arm, the outer side of 25 this pawl being preferably beveled, as at 24, to form a cam surface to coöperate with the shank as the latter is applied to the crank arm, the latch being thereby deflected laterally to permit the shank to enter the recess, 30 the pawl on the latch springing over the shank to lock it therein. The latch beyond the pawl is provided with an operating projection 25 adapted to be grasped by the fingers and retracted and thus release the shank 35 14 when it is desirable to remove the receptacle from the tank.

Rotary movement may be imparted to the crank arm in any suitable way, the shaft 18, in the present instance, extending through a 40 stuffing box 26 fitted in the wall of the tank, and on that portion of the shaft arranged on the exterior of the tank are fitted the tight and loose pulleys 27 and 28, respectively; the latter being adapted to receive a belt that is 45 capable of revolving the crank arm at the proper speed.

In operating the polishing or burnishing machine, constructed in accordance with the present embodiment of the invention, the 50 box or receptacle for the articles to be polished is preferably removed from the tank in order to facilitate the handling of the jewelry or other articles, this being accomplished by retracting the latch, lifting the angular-shaped shank from its recess in the end of the operating crank arm, and as the shoulder 20 is thereby released, the receptacle may be moved axially to withdraw the journal portion 10 from the bearing block 12. The 55 hinged lid 5 in the receptacle enables the jewelry or other articles to be readily inserted into the receptacle, and as the articles are placed in the receptacle, a suitable abrasive medium is introduced into the receptacle 60 which will have a rubbing action on the arti-

cles during the operation of the receptacle, steel balls or shot being used advantageously in many instances. The receptacle is introduced into the tank by placing the journal 10 at the rear end into the bearing block 12 and 75 introducing the angular shank 14 into the correspondingly shaped recess in the end of the crank arm, the latter being preferably in its uppermost position. As the shank enters the recess, the latch will spring behind it and 80 lock it in coöperative relation with the crank arm. The crank is supplied with a suitable cleansing or washing solution to a depth sufficient to submerge the receptacle during either a portion or the whole of its movement, the relative movements of the receptacle causing the solution to enter and leave the receptacle through the openings provided in its sides. As rotary movement is imparted 85 to the shaft 18, the receptacle containing the articles to be polished is given an oscillatory movement, that is to say, it will revolve on an axis coincident with its trunnion as well as on an axis arranged in alinement with the operating shaft. During the rotary movement of the receptacle, the ribs arranged on the insides thereof will serve to lift the articles at one side of the receptacle and permit them to roll or tumble therefrom to the bottom of the receptacle, the relatively reverse 90 arrangement of the ribs on the sides of the receptacle causing the articles to be pitched first toward one end thereof and then toward the other end, so that the articles are continually changing their position so that the 95 abrasive medium and the cleansing solution may reach every surface thereof. The inclination of the axis of the receptacle serves to elevate alternately the opposite ends thereof, the ribs serving in a measure to check the 100 rolling of the articles from one end of the receptacle to the other during each revolution, causing those at the bottom of the mass to remain substantially motionless while those toward the top of the mass change 105 their position.

A polishing or burnishing machine constructed in accordance with the present invention is very simple in construction so that it may be readily manufactured and sold at a reasonable price and is not liable to need repairs, and it is so constructed that a thorough polishing or burnishing action is given to every part of the surface of each article, especially adapting the machine for use in 110 polishing jewelry and other small articles, and the receptacle or box for the articles may be quickly removed and returned to the tank by the use of the latch connection between the receptacle and its supporting and operating devices, so that the application and removal of the articles is facilitated.

What is claimed is:—

1. In a machine for polishing jewelry, the combination with a tank adapted to contain 115

a suitable cleansing solution, of a receptacle revolvably mounted in the tank having a plurality of peripheral sides, and a series of inwardly projecting ribs secured to each peripheral side of the receptacle, the ribs on some of the sides having a pitch toward one end of the receptacle and those on the other sides having a pitch toward the other end of the receptacle, the ends of the ribs of the several sides abutting to form continuous zigzag channels extending circumferentially around the inside of the receptacle, screened openings being formed in the walls of the receptacle and communicating with the said channels and means for oscillating the latter about a longitudinal and a transverse axis.

2. In a machine of the character described, the combination with a suitable tank, of a receptacle revolvably mounted therein having a plurality of sides having screened openings therein, one of the sides being movable to permit access to the interior of the receptacle and a series of inwardly projecting ribs extending circumferentially about the inside of the receptacle.

3. In a polishing or burnishing machine, the combination with a tank adapted to contain a suitable cleansing solution, of a receptacle having axially extending trunnions at opposite ends, an operating shaft journaled in the tank having a crank arm provided with an eccentrically arranged angular socket co-operating with a corresponding annular end on one of the trunnions, and a bearing on the tank arranged in alinement with the said shaft and co-operating with the other trunnion of the receptacle, and a latch for locking the said crank arm and its co-operating trunnion.

4. In a polishing machine of the character described, the combination with a tank adapted to contain a suitable cleansing solution, of a receptacle adapted to receive the articles to be polished having axially extending trunnions at the opposite ends thereof, devices arranged within the tank and detachably co-operating with the trunnions of the receptacle for revolvably supporting the latter within the tank, and a spring actuated latch carried by one of the said supporting devices and co-operating with its respective trunnion for locking the receptacle in operative position within the tank when the receptacle is introduced therein.

5. In a polishing or burnishing machine, the combination with a tank adapted to contain a suitable cleansing solution, of a re-

ceptacle having axially extending trunnions at opposite ends, an operating shaft journaled in the tank having a crank arm a latch on the latter for detachably locking one of the trunnions thereto, and a suitable bearing for the other trunnion.

6. In a polishing or burnishing machine, the combination with a tank adapted to contain a suitable cleansing solution, of a receptacle having axially extending trunnions at opposite ends, an operating shaft journaled in the tank having a crank arm provided with a recess in one end, a latch adapted to co-operate with one of the trunnions on the receptacle for detachably locking the trunnion thereto, and a bearing on the tank co-operating with the other trunnion.

7. In a polishing or burnishing machine, the combination with a tank adapted to contain a suitable solution, of a receptacle for the articles to be treated having axially arranged trunnions at opposite ends, one of said trunnions having a reduced portion angular shaped in cross section and forming a shoulder on the trunnion, an operating shaft journaled in the tank having a crank at its inner end provided with a recess adapted to receive the angular portion of the trunnion, and co-operating at its inner side with the shoulder thereon, a latch for locking said crank arm and trunnion in co-operative relation, and a bearing for the other trunnion, the latter being held in co-operative relation with the bearing by the engagement of the shoulder on the other trunnion and the crank arm.

8. In a polishing or burnishing machine, the combination with a tank adapted to contain a suitable solution, of a receptacle having rows of zig-zag ribs extending around the interior surface thereof, an operating shaft journaled in the tank having a crank arm thereon non-rotatably connected at its end to one end of the receptacle, a latch for locking the crank arm in co-operative relation with the receptacle, and a bearing arranged substantially in alinement with said shaft and supporting the opposite end of the receptacle.

In testimony that I claim the foregoing as my own, I have hereunto affixed my signature in the presence of two witnesses.
